R. N. MCCLURE.
DIRECTION INDICATOR.
APPLICATION FILED OCT. 6, 1919.

Patented Jan. 25, 1921.

UNITED STATES PATENT OFFICE.

RODNEY N. McCCLURE, OF LOS ANGELES, CALIFORNIA.

DIRECTION-INDICATOR.

1,366,739.

Specification of Letters Patent. Patented Jan. 25, 1921.

Application filed October 6, 1919. Serial No. 330,900.

To all whom it may concern:

Be it known that I, RODNEY N. McCCLURE, a citizen of the United States, and a resident of Los Angeles, county of Los Angeles, and 5 State of California, have invented new and useful Improvements in Direction-Indicators, of which the following is a specification.

This invention relates to direction indicators of the character shown and described in my application for patent filed May 11, 1919, Serial Number 304,715, and has for a main object the provision of a combined direction indicator, stop signal, license number, display and tail light mechanism capable of operation from a convenient point in the vehicle for indicating a stop or change of direction of the vehicle.

Another object is to provide in a direction indicator, a main supporting housing capable of attachment to the usual tail support of a vehicle in the usual manner and on which all of the several elements hereinabove mentioned may be held.

25 A further object is to provide an improved and simplified means for actuating the signals, or indicators. Other objects will appear as the description progresses.

I attain the above objects of my invention 30 by means of the structure and mechanism shown in the drawings accompanying this application and forming a part hereof, similar characters of reference being used in the several views of the drawings and throughout the specifications for indicating the same and like parts.

In said drawings:

Figure 1 is a front elevation of my indicating mechanism, assembled for use;

40 Fig. 2 is a side elevation of the same;

Fig. 3 is a sectional elevation of the same on line 3-3 of Fig. 2;

Fig. 4 is a transverse sectional elevation;

Fig. 5 is a section of Fig. 3 on line 5-5.

45 I prefer to construct the body or the supporting and inclosing portion of my device in the form of a housing composed of a central, or main portion C, a front portion F and a rear portion R, of rectangular cross section. The front portion F incloses and supports a tail light L, mounted in a socket S, and has a colored lens I, removably held in the open end thereof. This portion is preferably of round cross section and the 50 outer wall 1 may have a plurality of openings 2, 2, formed therein over which transparent

substances, 3, 3, may be suitably held, for slightly illuminating the spaces at the sides and bottom of the housing F. The rear wall 4, of portion F, engages the end of housing 60 C, and a flange 5, is formed therearound which is adapted to fit over the end of housing C, as shown, screws 6, 6, being employed for holding portion F in the position shown and described.

65 Rear portion R has a wall 7 and flange 8, which fits over the rear end of housing C and is attached thereto by means of the screws 9; also an extension 10 is formed thereon with a recess 11, between the wall 12 of the 70 extension and wall 7 wherein a bar, rod, or other suitable member 13 may be inserted for holding the housings C, F and R in position on the vehicle. Member 13 may be clamped in position by means of a set screw 75 14, or otherwise.

The main or central member C has a pair 80 of arms 15, 15, formed on or attached to the top 16 thereof at the sides 17, 17, and a rod 18, is pivotally held in the upper ends of said arms and is also extended through and suitably connected with a flat vane 19, by means of lugs 20, 20, formed on said vane. One end of the rod 18 may be bent downwardly or provided with an arm 21, capable 85 of attachment with a suitable operating member or mechanism at the front of the vehicle by means of a rod or cable 22, or otherwise. The vane 19 has the word "Stop" printed or formed thereon for indicating 90 that it is the intention of the driver to stop the motion of the vehicle and said vane is adapted to be held normally as shown in Fig. 2, so that the legend thereon will be invisible to the drivers of vehicles behind. The 95 movement of arm 21 will turn the vane 19 a quarter of a revolution so that the full face thereof will be presented to the drivers of vehicles behind for the purpose of indicating an intention to stop, as stated.

100 The bottom 23 of housing member C, has a pair of spaced arms 24, 24, formed on or attached thereto for the purpose of holding a license number plate P which may be suitably attached thereto by means of screws 25, 105 or otherwise.

When my mechanism is in operating position on a vehicle, the stop signal 19 and number plate P will be positioned in parallel relation across the rear end of the vehicle, or transversely of the vehicle at the rear end so as to be exposed to full view, one

above the housing and the other below, as shown in Fig. 1. Intermediate signal 19 and plate P, I provide a pair of aligned indicators I and I', with "Right" and "Left" printed or formed thereon for indicating the intended change of direction to the right or left, as the case may be.

Signals I and I' are adapted to be normally held with edges presented to the view at the rear and are adapted to be turned a quarter of a revolution at each operation for presenting the full faces to view when a change of direction is about to be made. In Fig. 1, I have shown both indicators I and I' with their faces so turned to the view, but it will be understood that such an arrangement is only for the purpose of illustration and at no time during the use thereof will both signals be simultaneously displayed.

Signals I and I' are of a suitable form, preferably arrow-like as shown, and are attached at their inner ends to slotted heads 26, 26, of aligned shafts 27, 27, which are journaled in bearings 28, 28, on the opposite sides 17, 17. Shafts 27, 27, carry sprockets 29, 29, on their inner ends, which are adapted to be operated by means of sprocket chains, 30, 30, said chains terminating within the housing member C, and having their ends attached to coil springs 31, 31. Thus, when the lower ends of springs 31, 31, are attached as shown to lugs 32, 32, on the floor of the housing C, the tension of the springs will cause the sprockets to be held normally at one extreme of action. Pins, 33, 33, attached to shafts 27, 27, and movably engaging slots 34, 34, formed in the bearings 28, 28, internally of the housing serve to limit the action of the sprockets in an opposite direction.

The chains 30, 30 may be operated over idler sprockets 35, as indicated in Fig. 2, carried on the bottom of housing member C, or mounted on a suitable and convenient frame member 36 of the vehicle for directing the chains forwardly of the vehicle to points for connection with the operating means.

It will be observed that the openings at the sides and bottom of the tail light portion F of the housing provide ample light for the signals I and I', and the license plate P, and an opening may also be provided in housing member F, whereby light may be directed upon the stop signal 19.

The several housing members may be readily taken apart for cleaning or repairing any of the parts and a wire 37 may be inserted through an opening 38 in the floor

of the member C and connected with a plug 39 for supplying electric current to the lamp L. Other convenient and desirable features will be readily recognized by those familiar with the art.

It will be obvious that I have provided a slightly device of simple design and structure, capable of being produced at a moderate cost and adapted to combine the signaling and other elements usually provided on the rear end of a vehicle, such as tail light, license number plate, etc., on a single supporting frame or body, thus eliminating cumbersome devices and providing a practicable signaling system.

What I claim is:

1. A direction indicator including a housing, pivoted indicator means supported therein, operating means differentially connected with said indicator means, and a flexible element connected with said operating means and extending exteriorly of said housing, for actuating said indicator means, as described.

2. A direction indicator including a housing, indicator means pivoted therein, operating means connected with said indicator means within said housing, a flexible element connected with said operating means and extended at one end exteriorly of said housing, and means for resiliently connecting the inner ends of said flexible element with said housing, for restoring said operating means.

3. A direction indicator including a housing, shafts rotatably held in the walls of said housing, sprockets on the inner ends of said shafts, indicator vanes on the outer ends thereof, sprocket chains operating over said sprockets for turning said vanes, and springs attached to the ends of said chains for restoring said vanes to normal position after each operation.

4. A direction indicator including a housing, shafts rotatably held in the walls of said housing, sprockets on the inner ends of said shafts, indicator vanes on the outer ends thereof, sprocket chains operating over said sprockets for turning said vanes, springs attached to the ends of said chains for restoring said vanes to normal position after each operation, and means for limiting the operation of said vanes.

Signed at Los Angeles, county of Los Angeles, and State of California, this 16th day of September, 1919.

RODNEY N. MCCLURE.
